[57] CLAIM

The ornamental design for a surgical instrument, sub-
stantially as shown and described.

DESCRIPTION

FIG. 1 is a perspective view of the surgical instrument
embodying my new design;

FIG. 2 is a front elevation thereof;

FIG. 3 is a right side view thereof;

FIG. 4 is a rear elevation view thereof;

FIG. 5 is a left side view thereof;

FIG. 6 is a top plan view thereof;

FIG. 7 is a bottom plan view thereof.

The characteristic feature of my design resides in the
intersecting, dual planar, twisted tip configuration of
each blade member of the surgical instrument, as shown
in the drawings.FIG. 1
